UNITED STATES PATENT OFFICE

HENRY JOSEPH ROUND, OF MUSWELL HILL, LONDON, ENGLAND, ASSIGNOR TO THE RADIO CORPORATION OF AMERICA, OF NEW YORK, N. Y., A CORPORATION OF NEW YORK

THERMIONIC RECEIVING DEVICE FOR WIRELESS TELEGRAPHY AND TELEPHONY

Application filed March 31, 1920, Serial No. 370,175, and in Great Britain May 13, 1919. Renewed February 21, 1929.

This invention relates to improvements in thermionic receiving devices for wireless telegraphy and telephony and has for its object an increased magnification of signals. 5 In a divisional application, Serial No. 301,038, filed August 21, 1928, entitled Thermionic receiving devices, there is claimed that phase of the present invention which relates to the transformer per se. 10 According to this invention two valves are coupled by means of a transformer formed of resistance wire with an air core hereinafter called a resistance transformer and so arranged that the ratio of inductance to capacity is as great as possible. More than two valves may be arranged in cascade, each valve being coupled to the next by a transformer of the kind already described. In 15 some cases the two windings of a transformer 20 may be connected through a condenser.

The invention is illustrated by the accompanying drawing, Figure 1 of which shows a series of valves in cascade with transformers between them. Figure 2 shows a number 25 of curves illustrating the result obtained. In Fig. 1 F¹ F², F³, are filaments of three valves which are heated by a common battery B. The grid G¹ of the first valve and the filament F¹ are connected to an oscillatory circuit C 30 coupled to an aerial D. The anode A¹ of the first valve is connected to one end of a primary P¹ the other end of which is connected to the positive pole of a battery E in series with the battery B. The secondary S¹ is connected to the grid G² and filament F² of the second valve the anode A² of which is connected to one end of a primary P² the other end of which is connected to the positive pole 35 of the battery E. The secondary S² is connected to the grid G³ and filament F³ of the third valve. Each of the transformers P¹, S¹, P², S² is formed of resistance wire with an air core and the arrangements are such 40 that the ratio of inductance to capacity is as great as possible. The two windings of the transformer may be connected through condensers C¹, C², if desired. By increasing the number of valves and of transformers 45 50 the magnification of the signals may be in-

creased as desired or until the series begins to self-heterodyne.

The result obtained is illustrated in Figure 2 which shows four curves, the abscissas being wave lengths and the ordinates voltages. The 55 curve 1 shows the voltages obtained at the ends of the secondary of an air core copper transformer the primary of which is connected to the anode and filament of a valve, such as A¹ G¹ F¹, the transformer having a natural 60 period which is near the middle of the desired range of wave lengths. The curve 2 shows the voltages obtained when the transformer has such a resistance that the amplitude is greatly reduced but at the same time its maximum occurs at about the middle of the range 65 of wave lengths to be dealt with. It will be seen that this curve is much flatter than the curve 1, that is, the magnification is considerably reduced at the resonance point but 70 hardly at all at the limits of the wave lengths where magnification still occurs. Curve 3 shows the voltages that may be obtained by employing a number of valves and transformers as shown in Figure 1 while curve 4 shows 75 the effect when condensers such as C¹ C² are added.

By means of this invention it is possible to construct stable cascade amplifiers having a good range of wave length for waves even 80 as short as 80 metres.

What I claim is:—

1. A coupling device for thermionic amplifiers comprising a primary coil, a secondary coil inductively coupled thereto, and a condenser connected to adjacent ends of said coils, the inductive reactance of said device being high as compared to the capacitive reactance of said device.

2. A coupling device for thermionic amplifiers comprising a primary coil having an air core and constructed of wire having relatively high resistance, a secondary coil having an air core and also being constructed of wire having a relatively high resistance, said coils being inductively coupled, and a condenser connecting one end of said primary coil to one end of said secondary coil.

3. A coupling device for thermionic amplifiers comprising a primary coil constructed 100

of relatively high resistance wire, a secondary coil constructed of relatively high resistance wire, said coils being inductively coupled together, a condenser connected from one end of said primary coil to one end of said secondary coil, the inductive reactance of said device being high in comparison to the capacitive reactance of said device.

4. A coupling device for thermionic amplifiers comprising a primary coil containing inductive reactance and damping resistance, a secondary coil containing inductive reactance and damping resistance, said coils being provided with an air core and a condenser connected between one end of said primary coil and one end of said secondary coil.

5. A coupling device for thermionic amplifiers comprising a primary coil having inductive reactance, a secondary coil having an inductive reactance, each of said coils being highly damped and each offering a relatively high reactance to a predetermined frequency band, said primary and secondary coils being inductively coupled, means for capacitively coupling said coils, said means offering a relatively low reactance to said frequency band.

6. A coupling device for amplifiers of electrical oscillations designed to produce a substantially uniform voltage response over a predetermined range of frequencies comprising a primary coil, a secondary coil inductively coupled thereto, a condenser connected between one terminal of said primary coil and one terminal of said secondary coil, said coils having an inductive reactance relatively high with respect to the capacitive reactance of said condenser.

7. In a system of the class described, means to couple two three-electrode vacuum tubes together, whereby to permit a substantially uniform transfer of energy from one tube to the other over a predetermined range of frequencies, said means comprising a primary coil connected to one vacuum tube, a secondary coil connected to another vacuum tube and coupled to said primary coil, said primary coil and secondary coil coupled thereto having together a high ratio of inductance to capacity, and a capacity other than the capacity inherent in said coils connected from the plate of one vacuum tube to the grid of the other vacuum tube.
